US00D979938S

(12) **United States Design Patent** (10) Patent No.: **US D979,938 S**
(45) Date of Patent: **** Mar. 7, 2023**

(54) **LUGGAGE**(71) Applicant: **JRSK, Inc.**, New York, NY (US)(72) Inventors: **Sam Naparstek**, New York, NY (US);
Christie Suozzo, New York, NY (US);
Diana Ong, New York, NY (US);
Jessica Lee, New York, NY (US)(73) Assignee: **JRSK, Inc.**, New York, NY (US)(**) Term: **15 Years**(21) Appl. No.: **29/702,702**(22) Filed: **Aug. 21, 2019**(51) LOC (14) Cl. **03-01**

(52) U.S. Cl.

USPC ..... **D3/279; D3/289**(58) **Field of Classification Search**USPC D3/279, 281, 318, 285, 301, 294, 321,
D3/273

CPC Y10T 16/451; A45C 2005/032; A45C 5/03

Primary Examiner — April Rivas(74) *Attorney, Agent, or Firm* — Wolf, Greenfield & Sacks, P.C.(57) **CLAIM**

The ornamental design for a luggage, substantially as shown and described.

DESCRIPTION

FIG. 1 shows a top, front, right side perspective view of the Design.

FIG. 2 shows a front view of the Design.

FIG. 3 shows a rear view of the Design.

FIG. 4 shows a right side view of the Design.

FIG. 5 shows a left side view of the Design.

FIG. 6 shows a top view of the Design; and,

FIG. 7 shows a bottom view of the Design.

Any broken lines shown in the drawings represent unclaimed portions of the luggage and form no part of the claimed design.
